SHEET MAKING MACHINE

Christian Paulsen, Clifton, N. J., assignor to
 Boorum & Pease Company, Brooklyn, N. Y.,
 a corporation of New Jersey

Application April 13, 1934, Serial No. 720,472

14 Claims. (Cl. 93—1)

This invention relates to machines for perforating and cutting sheets for "loose leaf" books from continuous rolls of paper and it is an object of this invention to provide a machine of the type described which is arranged to attach gummed linen strips to one edge of each of a plurality of continuous paper webs, the linen strips to be perforated for receiving the ring fasteners, and the combined paper webs and linen strips being cut in suitable lengths for pages. It is also an object of this invention to provide means for securing the linen strips to the paper webs in a continuous operation and by means of reasonable dimensions and it is also an object of this invention to provide in a machine of the type described means for attaching a linen strip to the paper web in a continuous operation and feeding the combined web and strip at intervals to a periodically operating punching and severing means.

In the drawings—

Figs. 1 and 2 are partial views which, when arranged adjacent, show in side elevation a machine constructed in accordance with this invention;

Figs. 3, 4, and 5 are partial views, partly in section and partly diagrammatical, which when arranged in order show the paths of movement of the various paper webs and linen strips through the machine;

Fig. 6 is a horizontal section taken on the line 6—6 of Fig. 2 showing in plan view the driving means and the first set of paper drawing rolls;

Figs. 7 and 8 are sectional views showing in plan view the means for applying tension to the paper web at position A in Fig. 3 and position B in Fig. 5, respectively;

Figs. 9 and 10 are views in elevation showing the means for operating the tensioning means shown in Figs. 7 and 8, respectively;

Fig. 11 is a fragmentary view, partly in elevation and partly in vertical section, showing the means for gumming the linen strip;

Fig. 12 is a top plan view of the structure shown in Fig. 11, parts being broken away to show other parts more clearly;

Fig. 13 is a view in elevation looking from the right in Fig. 11, parts being broken away to show other parts more clearly;

Fig. 14 is a vertical section taken as on line 14—14 of Fig. 11;

Fig. 15 is a partial broken plan view showing the means for guiding the paper webs and the gummed linen strips at the time of placing the webs and strips together;

Fig. 16 is a partial broken view in elevation showing the means of guiding the paper webs and linen strips when the linen strips first run with the paper webs;

Fig. 17 is a plan view of a length of the attached paper webs and linen strips parts of the webs and strips being broken away to show the difference in the widths of the various paper webs and the various linen strips;

Fig. 18 is a plan view of a single paper web with the linen strip attached thereto and showing the successive steps of punching the linen strip, notching the web and strip to form the round corners and severing the finished sheet or page from the combined web and strip; and

Fig. 19 is a partial perspective view of a plurality of groups of the finished sheets or pages as cut from the continuous webs and strips, parts of some of the sheets being broken away to more clearly show the difference in the widths of the paper portions of the finished sheets and of the linen portions of the finished sheets.

As shown in the drawings a machine constructed in accordance with this invention comprises a lower or base frame 1, formed of a plurality of spaced longitudinal members suitably connected at intervals, and an upper frame 2 of similar longitudinal members similarly connected and having parts thereof at different elevations from the base frame 1, the frame 2 being supported by pairs of vertical members 3, 4, 5, and 6. Mounted upon the base frame 1, adjacent an end thereof, are a plurality of pairs of standards 8, 8a, 8b, and 8c, which serve to support the shafts upon which the rolls of papers 10a, 10b, 10c, and 10d are rotatably supported. At the end of the frame 1 adjacent the standards there is secured a bracket or frame comprising a pair of upright members 34 in which are rotatably supported a plurality of sets of draw rolls 38 driven by means of belt 31 and pulleys 32 and 33 from a shaft of the draw rolls 18 journaled in a frame 20 supported upon the base frame 1 adjacent the other or control end of the base frame 1. Also mounted upon the base frame 1 at the control end is a driving motor 22 connected by a chain 23 to a change speed gearing 24 which is, in turn, connected by a chain 25 to the draw rolls 18. The change speed gearing, as shown, is of the adjustable cone pulley type comprising the adjustable cone pulleys 35 and 36 connected by belt 37 and adjusted by means of the levers 38 and 39 which are operated by the screw 40 and the handle or operating wheel 41. Pulleys 36 are splined on the shaft 42, driven by the chain 23

25

55

from the motor 22, while pulleys 35 are splined on the shaft 43 connected by chain 25 to the shaft 44 which drives the draw rolls 18. While a change speed gearing of a particular construction has 5 been shown it is to be understood any suitable construction of change speed gearing may be used.

Mounted upon the upper frame 2 are the standards 50 which support the ends of the guide rods 51. As shown in Fig. 16 each of these guide rods is provided with a pair of spaced collars 52 which divide the guide rods into uneven portions, the wide portion serving to guide the paper webs from the rolls 10a, 10b, 10c, 10d, while the narrow portions between the collars are provided 15 with rollers and serve to guide the linen strips which are attached to the respective paper webs, the paper webs passing over the guide rods while the linen strips pass beneath the guide rods.

Also mounted on the upper frame 2 are spaced 20 brackets 54 which serve to support the guide rods 55. As shown in Figures 11 to 14 an end of each guide rod 55 is hollowed or recessed, as at 25 56, and communicates with a passage 57 in the boss 58 in which the end of the guide rod 55 is mounted. Passage 57 in the boss 58 communicates with the interior of a receptacle 59 supported from a bracket 54 and which holds the gum for application to the linen strip. The gum is supplied from the receptacle 59 through the 30 passage 57, recess 56 to a slot or opening 60 in the wall of the guide rod 55 and a slot 63 in the boss. The boss 58 is partly cut away to form a flat upper surface, as at 62, with a slightly projecting flat rim about the slot 63. Screw 61 35 mounted in the rod 55 and engaging in a slot in the boss 58 limits rotation of the rod 55 sufficient to open and close the slot 60. Secured to the boss 58 is a bracket 64 having the ears 65 in which is pivotally mounted the arm or finger 66 carrying 40 the presser plate 67 secured to the finger 66 by the set screws 68. Movement of the presser plate to the mouth 63 is limited by the adjustable screw 69. Fixedly mounted in the bracket 64 is the rod 70 having a roller 71 thereon guided between the adjustable collars 72 and 73 and adjustably mounted in the bracket 64 is a rod 75 45 having a collar 76 thereon against which bears a spring 77 confined between the collar 76 and the bracket 64, the spring 77 tending to move the rod 75 outwardly and the movement thereof being limited by the wing-nut 78. As shown in Figures 11 to 14 the linen strips pass beneath the roller 71 between the collars 72 and 73 and pass over the rod 75 adjacent to the collar 76, the 50 collars 76 and 72 serving to guide the linen strips so that one edge thereof passes over the mouth 63 to receive the gum from the receptacle 59 which wells up through the mouth, the linen strip being held in contact with the mouth by the presser 67. 55

Also mounted upon the upper frame 2 is a casing 80 having openings at opposite ends thereof for the passage of the webs and strips and provided with heating units 81. As shown these heating units are indicated as being electrically 60 heated but it is to be understood that other suitable types of heating units may be installed, if desired. Also mounted upon the upper frame 2 are the brackets 82 which serve to support the ends of guide rods and shafts for the draw rolls 70 65 83, the drive rolls being driven by chain 84 and suitable sprockets from the shaft 86 of the draw rolls 18 which drives the pulleys 33 and belt 31 so that all of the draw rolls are driven from the same drive mechanism, the sprockets and pulleys 75 being chosen so as to drive the draw rolls at the

same speed. The speed of the draw rolls may be adjusted by adjusting the change-speed gearing 24 which, when operated, adjusts the speed of all of the draw rolls simultaneously.

Also mounted upon the upper frame 2 is a 5 punch 88, a notching or cornering device 89, a set of draw rolls 90 and a cut-off mechanism 91, the punch 88, cornering device 89 and the cut-off device 91 being operated by means of a cam shaft 92 driven through gears 93 and 94 from a shaft 10 10 96 journaled in the frame 2 and driven by chain 95 and suitable sprockets 96 and 97 from the drive motor 22. The draw rolls 90 are operated by means of the rack 98 and pinion 99, connected through a pawl and ratchet (not shown) with the shaft 100 so that the pinion 99 may drive the shaft 100 in one direction only as the rack 98 is reciprocated through its connection with the shaft 96, this giving to the draw rolls 90 a periodic operation so as to move the webs and strips 20 a predetermined distance forward for each revolution of the shaft 96, the webs and their attached strips not moving while the rack is being retracted for a subsequent forward operation. The operation of the cam shaft 92 is so related to 25 the operation of the rack 98 that the punch 88, cornering device 89 and the cut-off mechanism 91 are operated during the period when the webs are at rest.

Mounted in the uprights 34 are cross-bars 101 30 which support plates 102 over which the webs pass and bearing upon the webs are felt surfaced tensioning devices 103 carried by shafts 104 also mounted in the uprights 34 and operated by springs 105 and crank arms 105a to hold the felt 35 covered tensioning devices 103 in engagement with the webs. In the brackets 82, similar web-tensioning devices are mounted comprising cross-bars 106 over which the webs pass and against which the webs are pressed by the felt surfaced 40 tensioning devices 107 mounted upon the shafts 108 and operated by springs 109 and crank arms 109a to bring the tensioning devices 107 in contact with the webs.

In the operation of this device the webs a, b, 45 c, d, there being four used in the machine illustrated, fed from the rolls 10a, 10b, 10c, and 10d pass beneath guide rods 12 carried by the uprights 4 and are separated so as to pass over individual guide rods 13, 14 in the brackets 13a and 14a, respectively, carried from the frame 2. The webs also pass over the guide rods 15 and past the guide rods 16, supported from the frame 20 of the draw rolls 18. At the draw rolls 18 the webs come together and are directed towards the other end of the machine, passing over guide rods 26 and 27 supported in the base frame 1. At the other end of the machine the webs are separated to pass beneath the guide rods 28 supported in the uprights 34. From the guide 34 the webs pass between individual sets of draw rolls 30, which are operated as a train, and sufficient web is drawn from each roll to form a loop, as at 110, before they are passed over the guide rolls 111 and beneath the tension devices 103, all supported in the uprights 34. From the tension devices 103 the webs pass to the guide rods 51 supported in the uprights 50. At these guide rods the webs meet with the strips of linen which are to be secured thereto, the linen strips a', b', c', and d' passing 55 beneath the guide rods and at one side of the paper webs as shown in Figure 16. It will be noted that the paper webs pass over a guide rod which is below the guide rod carrying the roller guiding the corresponding linen strip. 60 65 70 75 80 85 90 95 98 100 102 104 105 106 107 25510 25511 25512 25513 25514 25515 25516 25517 25518 25519 25520 25521 25522 25523 25524 25525 25526 25527 25528 25529 25530 25531 25532 25533 25534 25535 25536 25537 25538 25539 25540

- From the guide rolls on rods 51 the linen strips pass beneath the guide rollers 71 and over the guide rods 75 to the rods 55 where the edges of the linen strips are gummed, after which the linen strips pass beneath guide rods 114 mounted in the brackets 121 and over the guide rods 115 while the paper webs pass from above the guide rods 51 beneath guide rods 116 and over the guide rods 115, the paper webs being guided by collars 117 and 118 on the guide rods 116 while the linen strips are guided by collars 119 and 120 on the guide rods 114 so as to place the gummed portions of the linen strips in overlapping relation with the paper webs to the desired extent so that upon the strip and the web passing over the guide rods 115 the gummed portions of the linen strips are brought into contact with the edges of the paper webs and the linen strips secured to the paper webs.
- From the guide rods 115 the combined webs and strips pass the guide rods 123 and 124 and then pass through the heating chamber 80, the purpose of which is to properly dry the gum which secures linen strips to the paper webs and in order to accomplish this without undue length of heating chamber or machine, the combined webs and strips are passed about rollers 125 supported in the frame 82 and are returned through the heating chamber 80 to be passed around rollers 126 supported in the frame 54 and again passed through the heating chamber 80, the repeated passage of the combined webs and linen strips serving to thoroughly dry the gum and unite the webs and strips. From the heating chamber 80 the combined webs and strips pass about the rollers 127 and 128 supported on the frame 82 and pass to the draw rolls 83 which draw rolls, it will be noted, operate only upon the paper webs and not upon the linen strips, the linen strips being moved solely through their adhesion to the paper webs. The draw rolls 83 deliver the combined webs and strips to slack loops, as at 130, from which loops the webs and strips pass over the rollers 131 and 132 and past the guide plate 134 to the tensioning devices 107. From the tensioning devices the combined webs and strips are drawn by the draw rollers 90 through the punch 88 and the notching or cornering device 89 and delivered to the cutting-off or severing device 91, the punching device punching holes for the ring fasteners in the linen strips and the cornering device notching the opposite edges of the combined strips and webs, as shown at 135 in Fig. 18, while the severing device 91 cuts the webs and strips at predetermined lengths to form the finished sheets.
- The linen strips which are delivered to the machine, with as little friction and resistance as possible, are unreeled from the rolls in which they come into receptacles from which they are drawn to the guide rods 51 by the adhesion of the gummed portion thereof to the paper webs after they have passed the guide rod 115. The various strips and webs differ in width so that when assembled in a binder the pages will be grouped as in Fig. 19 with the overlapped portions staggered decreasing the bulk of a number of pages at the joint of the web and strip and permitting of the insertion of a greater number of pages in a binder.
- The separate adjustment of the collars on the guide rods 51 and 116 and 114 permit of this difference in the widths of the strips and web without interfering with the operation of the machine. It will also be noted that immediately prior to attaching the linen strip to the paper web the

paper webs and strips are kept separated from one another in order that the webs and strips may not become charged with static electricity and interference with the control of the paper webs and linen strips by this condition be avoided.

I claim—

1. In a machine of the class described means for continuously attaching a web and strip, means guiding said web to said strip attaching means, draw rolls relieving said web of all tension in advance of said guiding means, means periodically advancing the joined web and strip to punching and severing means and means heating the joined web and strip during continuous movement thereof intermediate the joining of the web and strip and the severing of the joined web and strip.
2. In a machine of the class described, means for continuously attaching a plurality of webs and strips individually, means periodically operating upon the plurality of joined webs and strips at portions thereof which are at rest, guides for positioning the webs for said means and draw rolls relieving the webs of all tension in advance of said guides.
3. In a machine of the class described, means for continuously advancing a plurality of webs, means for attaching strips individually to the moving webs, means for punching and severing the combined webs and strips, means for advancing said webs and strips periodically to said punching and severing means, means guiding said webs to said punching and severing means and draw rolls relieving the webs of all tension in advance of said guiding means.
4. In a machine of the class described, means for continuously advancing a plurality of webs, means for attaching strips individually to the moving webs, means guiding said webs to said strip attaching means, draw rolls relieving said webs of all tension in advance of said guiding means, means for punching and severing the combined webs and strips, means for advancing said webs and strips periodically to said punching and severing means and means for heating the combined webs and strips intermediate the attaching of said webs and strips and the punching thereof.
5. In a machine of the class described, means for continuously advancing a plurality of webs, means continuously gumming one edge of each of a plurality of strips, means continuously attaching said gummed strips individually to edges of said webs, means for advancing the attached strips and webs periodically, means operating upon the attached strips and webs between successive periodic movements, guiding means for said webs and means relieving the webs of tension in advance of said guiding means.
6. In a machine of the class described, means for continuously advancing a plurality of webs, means continuously gumming one edge of each of a plurality of strips, means continuously attaching said gummed strips individually to the edges of said webs, means for advancing the attached strips and webs periodically, means operating upon the attached strips and webs between successive periodic movements, means heating the attached strips and webs during their continuous movement, guiding means for said webs and means relieving the webs of tension in advance of said guiding means.
7. In a machine of the class described, means for continuously advancing a web and strip, means for continuously gumming an edge of the

strip, means continuously attaching said gummed strip to an edge of said web, means holding said web under tension during the attaching of said strip, means guiding said web for the attaching of the strip, web advancing means relieving the web of tension in advance of the guiding means, means for advancing said combined web and strip periodically, means for operating upon said combined web and strip intermediate successive periodic movements and means holding said combined web and strip in tension while being operated upon.

8. In a machine of the class described, means for supplying a plurality of webs, means for attaching continuous strips to said webs, means for heating the attached webs and strips, guide means for said webs, a plurality of sets of draw rolls engaging said webs at different points for continuously advancing said webs and strips, said draw rolls relieving said webs of tension in advance of said guiding means and driving means for said drawing rolls comprising a variable gearing for simultaneously regulating the speed of all sets of drawing rolls.

9. In a machine of the class described, means for continuously advancing a web, means continuously gumming a strip, means attaching said strip and web, means holding said web in tension during the attaching of said strip, means guiding said web and web advancing means relieving the web of tension in advance of said guiding means.

10. In a machine of the class described, means for continuously drawing a web from a roll, tensioning means for said web, means continuously drawing said web under tension and means continuously attaching a strip to said web while said strip is in tension, said drawing means maintaining the web relieved of tension in feeding to said tensioning means.

11. In a machine of the class described, means continuously advancing a web, means attaching a strip to said web, tensioning means, means advancing said joined web and strip periodically under tension and means operating upon said joined web and strip at intervals while said web and strip are at rest, said advancing means maintaining said web and strip relieved of tension in feeding to said tensioning means. 5

12. In a machine of the class described, means 10 for continuously attaching a plurality of webs and strips individually, means operating upon the plurality of joined webs and strips at portions thereof which are at rest, said webs being under tension during the attaching of the strips 15 and when being operated upon, means guiding said webs individually to said strip attaching means and to said means operating upon said webs and strips and means for drawing said webs to form slack loops thereof immediately in advance of said guiding means. 20

13. In a machine of the class described, means for drawing a plurality of webs from rolls, means for continuously attaching said webs and a plurality of strips individually, means tensioning 25 said webs individually during the attaching of said strips, guiding means for positioning said webs and strips and means drawing said webs to relieve said webs of all tension at the guiding means. 30

14. In a machine of the class described, means for drawing a plurality of webs intermittently, means tensioning said webs individually, means for operating on said webs while at rest, means guiding said webs to said tensioning means and 35 means drawing said webs continuously and relieving said webs of all tension in advance of said guiding means. 40

CHRISTIAN PAULSEN.
